HEADBOARD FOR BEDS

John O. Van Koert, New York, N. Y., assignor to Drexel
Furniture Company, Drexel, N. C., a corporation of
Delaware

Application August 2, 1955, Serial No. 37,263

Term of patent 7 years

(Cl. D5—4)

Fig. 1.

Fig. 2.

Fig. 3.

Figure 1 is a front perspective view of a headboard for beds, showing my new design;

Figure 2 is an end view thereof; and

Figure 3 is a front perspective view showing the opposite end of the headboard with the sliding doors adjusted to a different position than is shown in Figure 1.

I claim:

The ornamental design for a headboard for beds, as shown.
